United States Patent Office

Des. 194,116
Patented Nov. 20, 1962

194,116

PITCHER OR SIMILAR ARTICLE

Martin Schnur, West Orange, and Mel Appel, Murray Hill, N.J., assignors to Deka Plastics, Inc., Elizabeth, N.J.

Filed May 8, 1962, Ser. No. 70,035

Term of patent 14 years

(Cl. D44—21)

FIG. 1

FIG. 2

FIG. 4

FIG. 5

FIG. 3

FIGURE 1 is a front elevational view of a pitcher or similar article showing our new design; the rear and front elevational views being mirror images of each other;

We claim:

The ornamental design for a pitcher or similar article, as shown and described.
